Frederick C. Ruppel, Grand Rapids, Mich., assignor to Wheary Trunk Company, Racine, Wis., a corporation of Wisconsin

Application November 30, 1939, Serial No. 88,578

Term of patent 7 years

To all whom it may concern:

Be it known that I, Frederick C. Ruppel, a citizen of the United States, residing at the city of Grand Rapids, in the county of Kent and State of Michigan, have invented a new, original, and ornamental Design for a Traveling Case, of which the following is a specification, reference being had to the accompanying drawing, forming a part thereof.

Fig. 1 is a perspective view of a traveling case showing my new design.

Fig. 2 is a side elevational view of the same.

Fig. 3 is a top plan view of the same, and

Fig. 4 is an end elevational view.

I claim:

The ornamental design for a traveling case, as shown.

FREDERICK C. RUPPEL.
